US00D413597S

United States Patent [19]

Oba

[11] Patent Number: Des. 413,597
[45] Date of Patent: ** Sep. 7, 1999

[54] COMBINED TELEPHONE AND COMPUTER

[75] Inventor: **Haruo Oba**, Tokyo, Japan

[73] Assignee: **Sony Corporation**, Tokyo, Japan

[**] Term: **14 Years**

[21] Appl. No.: **29/081,570**

[22] Filed: **Jan. 6, 1998**

[51] LOC (6) Cl. **14-03**

[52] U.S. Cl. **D14/144; D14/100; D14/138**

[58] Field of Search **D14/137, 106, D14/138, 107, 147-148, 247-248, 250, 240, 140-142, 100, 115, 144; 379/433, 434, 419, 420, 428, 440, 110.01, 112; 455/550-575, 90; 364/705.05**

[57] CLAIM

The ornamental design for a combined telephone and computer, as shown and described.

DESCRIPTION

FIG. 1 is a perspective view of a combined telephone and computer showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a rear elevational view thereof; and,

FIG. 8 is another front elevational view thereof wherein the dial and screen portion is in the open position.
